United States Patent

Des. 235,341
Patented June 10, 1975

235,341

HANDLE FOR WATER CLOSETS OR THE LIKE

Stanley F. Korol, 457 Shepard Road,
Mansfield, Ohio 44907

Filed Dec. 26, 1973, Ser. No. 428,293

Term of patent 14 years

Int. Cl. D23—01; D8—06
U.S. Cl. D23—29

FIG. 1.

FIG. 2.

FIG. 3

FIG. 4

FIG. 5

FIG. 1 is a perspective view of a handle for water closets or the like according to this invention;

FIG. 2 is a side elevational view of the handle;

FIG. 3 is a plan view of the handle;

FIG. 4 is a front view of the handle; and

FIG. 5 is a rear view of the handle.

The broken lines are for illustrative purposes only.

I claim:

The ornamental design for a handle for water closets or the like, as shown and described.
